ABSTRACT

A method for drilling a well using high-speed rotation of the drill bit and drill pipe wherein catastrophic vibration of the drill pipe during high speed rotation is at least in part prevented by the use of a drilling fluid whose ratio scar width/(plastic viscosity)^{1/2} is no greater than about 4.

7 Claims, No Drawings

DRILL PIPE VIBRATION CONTROL IN ROTARY DRILLING

BACKGROUND OF THE INVENTION

Heretofore in rotary drilling a wellbore in the earth, the drilling bit and the drill pipe which supports the bit in the wellbore are both conventionally rotated during drilling at rates of from about 100 to about 250 r.p.m. Such drilling rigs, in the petroleum industry, generally drill boreholes having diameters of from about 8% to about 13% inches.

As an exploratory tool, it can be desirable to employ what is known as a "slimhole" drilling technique wherein the borehole has a diameter of up to about 6 inches, preferably from about 2 to about 4 inches. With slim hole drilling it is desirable to use higher than conventional rotation rates for the drill bit. For example, rotation rates of at least 400 r.p.m. and as high as 1,500 to 3,000 r.p.m. are desirably employed to achieve shorter drilling time.

By drilling small diameter boreholes with high-rotation speed, larger numbers of exploratory wells can be drilled more economically. In addition, the rig used is lighter thereby allowing for more economical movement of the rig from one drilling location to another.

However, an omnipresent problem with the high-rotation rates of the drill pipe in the small diameter borehole has been what is termed "catastrophic" vibration of the drill pipe. At rotation rates of greater than 400 r.p.m. the drill pipe tends to bounce from one side of the borehole to the other at a faster and faster rate until catastrophic vibration sets in and results in failure of the drill pipe, usually by twisting off one section of drill pipe from an adjacent section of drill pipe at their coupling joint.

Thus, slim hole drilling using the most economical rotation rate for the drilling bit and pipe is not feasible from a practical standpoint unless catastrophic vibration of the drill pipe during rotation is avoided.

SUMMARY OF THE INVENTION

It has now been found that the drilling fluid employed in the slim hole drilling process can be an aid in preventing catastrophic vibration of the drill pipe if the drilling fluid has a ratio of its scar width to the square root of its plastic viscosity, $(\text{plastic viscosity})^{1/2}$, which is no greater than about 4, preferably equal to or less than 4.

It has been further found that additional aids in preventing catastrophic vibration of the drill pipe include maintaining the pH of the drilling fluid at a value no greater than about 9 and/or maintaining the total of undissolved solid material having a specific gravity of no greater than 3.0, which material is dispersed in the drilling fluid, at a value no greater than about 14 weight per cent based on the total weight of the drilling fluid.

By following the teachings of this invention, a drilling fluid is obtained which can be an aid in preventing, if not totally preventing, catastrophic vibration of the drill pipe during rotation thereof at speeds of at least 400 r.p.m., including, but not limited to, speeds up to 3,000 r.p.m.

Accordingly, it is an object of this invention to provide a new and improved method for drilling a wellbore at high-rotation speeds while avoiding catastrophic vibration of the drill pipe. It is another object to provide a new and improved method for preventing catastrophic vibration of drill pipe when rotated at speeds of at least 400 r.p.m. It is another object to provide a new and improved method for drilling a wellbore utilizing high-speed rotation of the drill pipe and bit and a drilling fluid which aids in preventing catastrophic vibration of the rotating drill pipe.

Other aspects, objects, and advantages of this invention will be apparent to those skilled in the art from this disclosure and the appended claims.

DETAILED DESCRIPTION OF THE INVENTION

The ratio of scar width/(plastic viscosity) $^{1/2}$ is determined according to this invention by first obtaining a scar width value for the drilling fluid. This is done using an EP Mud Tester model 211 which is available commercially from the Baroid Division of the National Lead Company. This tester is designed to measure the lubricating properties of drilling fluids by mounting a hardened steel test cup (Rockwell C scale hardness of 58-62) on a rotating shaft and forcing a steel wear block (Rockwell C scale hardness of 58-62) against the test cup with a predetermined load while the test cup and wear block are immersed in the drilling fluid being tested. The load is applied with a torque arm that is operatively connected to the wear block, the torque arm containing a torque gauge calibrated in inch pounds. The friction load is read on an ammeter scale indicating the electrical current consumption of the driving motor. The motor is run at 1,400 r.p.m. which amounts to a surface velocity of the test cup of 507 feet per minute, the test cup diameter being 1.378 inches. Each test cup is used only once and a fresh spot is selected on the wear block for each run.

In the actual test itself, a friction load corresponding to three amps is applied with the torque arm and the run continued for 20 seconds holding the ammeter reading constant by increasing the load applied to the torque arm. The width of the scar formed on the wear block by the test cup is then measured in hundredths of an inch. Each test is carried out under ambient conditions of temperature and pressure using sufficient drilling fluid to completely immerse the test cup.

After the scar width is measured, the plastic viscosity of the drilling fluid is obtained in the conventional manner using a 115-volt motor-driven viscometer and rotor sleeve and speeds of 300 and 600 r.p.m. as fully and completely disclosed in the American Petroleum Institute's Standard Procedure for Testing Drilling Fluid Bulletin, API RP 13B, First Edition, Nov., 1962, issued by American Petroleum Institute Division of Production Dallas, Dallas, Texas, Pages 5 and 6.

The determination of plastic viscosity of drilling fluids in the manner described above is a conventional procedure well known in the art, and generally involves immersing the rotor sleeve of the viscometer in the drilling fluid up to the line inscribed on the sleeve, rotating the sleeve at 600 r.p.m. and reading the dial when it reaches a steady value followed by shifting the rotating speed from 600 to 300 r.p.m. and again reading the dial when it reaches its steady value. Plastic viscosity in centipoises is the 600 r.p.m. reading minus the 300 r.p.m. reading.

The square root of the plastic viscosity is then taken and divided into the scar width. If the resulting value is no greater than about 4 the drilling fluid has adequate capacity for at least aiding in preventing catastrophic vibration of rapidly rotating drill pipe.

If the drilling fluid does not meet the above ratio requirement, the composition of the drilling fluid can be altered to meet that requirement. For example, the plastic viscosity can be increased by adding to the drilling fluid varying amounts or combinations of bentonite, carboxy-methyl-cellulose, attapulgite, and other clays as is well known in the art. Similarly, the removal of these materials can decrease the plastic viscosity.

The scar width value can be varied by increasing or decreasing the lubricity of the drilling fluid. This can be achieved by adding to or removing from the drilling fluid one or more materials which have a lubricating function. For example, to reduce the scar width, conventional additives known in the art as Extreme Pressure (EP) additives can be employed. Such additives are fully and completely disclosed in the Society of Petroleum Engineers of AIME Paper No. 1152-G, 1958, entitled Increased Drill Bit Life Through Use of Extreme Pressure Lubricant Drilling Fluid, by Rosenberg and Tailleur.

Suitable EP additives include sulfurized diisobutylene, mixtures of asphalt and bentonite, mixtures of asphalt and sul-

furized diisobutylene, mixtures of asphalt and lead sulphite, mixtures of asphalt and sulfurized fatty acids, mixtures of fatty acids, linseed oil, castor oil, sulfurized fatty acids, sulfurized lard oil, sulfurized glycerol trioleate, alkali metal oleates, oleic acid, sulfurized oleic acid, sulfurized tall oil, and the like.

The drilling fluids employed can be either oil base or water base or combinations thereof such as water-in-oil or oil-in-water emulsions which are all known in the art. The scar width and plastic viscosity of these drilling fluids, whether they contain oil or water or combinations thereof, can be varied in order to meet the ratio requirements of this invention by using the teachings set forth hereinabove and/or other techniques known in the art.

Drilling fluid or fluids which meet the ratio requirement of this invention can be employed in the drilling process as the sole drilling fluid, substantially the only drilling fluid present, or in any lesser amount in combination with other drilling fluids which do not meet the ratio requirement so long as the drilling fluid or fluids which do meet the ratio requirement are employed in the drilling process in an amount at least sufficient to aid in preventing catastrophic vibration of the drill pipe. Generally, the drilling fluid or fluids meeting the ratio requirement of this invention will be employed in a major amount relative to other drilling fluids used.

It has further been found that in addition to meeting the ratio requirement of this invention, the ability of a drilling fluid to combat catastrophic vibration of the drill pipe at rotation rates of greater than 400 r.p.m. is enhanced if the drilling fluid has a pH value of no greater than 9 and/or the drilling fluid contains undissolved particulate solid material (having a specific gravity of less than 3.0) dispersed therein in amounts no greater than about 14 weight per cent based on the total weight of the drilling fluid which meets the ratio requirement.

EXAMPLE

A drilling fluid composed of a major amount of water, an emulsifying amount of soap, a lubricating amount of sulfurized tall oil, and a minor amount of diesel oil had a scar width of 7.5 hundredths of an inch and a plastic viscosity of 2.5 centipoises so that its ratio scar width/(plastic viscosity)^{1/2} equaled 4.74. The scar width and plastic viscosity were determined as set forth hereinabove.

The drilling fluid was employed in drilling a wellbore 3 1/4 inches in diameter using a drill pipe having 1.9 inches outside diameter and a diamond bit. The drill pipe and bit were rotated at 400 r.p.m.

Eleven hundred feet of wellbore was drilled using the above conditions and drilling fluid. Catastrophic vibration caused five drill collar separations and failures.

By adding 3 weight percent bentonite to the above drilling fluid, the ratio scar width/(plastic viscosity)^{1/2} was decreased to 1.5 (scar width 6 and plastic viscosity 16). With this drilling fluid, drilling was continued under the same Conditions as set forth above in this example except that the pipe and bit were rotated at 1,100 r.p.m. and no catastrophic vibration was encountered.

Reasonable variations and modifications are possible within the scope of this disclosure without departing from the spirit and scope of this invention.

The embodiments of the invention in which an exclusive property or privilege is claimed are defined as follows:

- 20 1. In a method for drilling a wellbore in the earth wherein the drilling bit and at least part of the drill pipe is rotated during drilling at speeds of at least about 400 r.p.m., the improvement comprising employing at least during drilling a drilling fluid whose ratio scar width/(plastic viscosity)^{1/2} is no greater than about 4, said drilling fluid being employed in an amount at least sufficient to aid in preventing catastrophic vibration of the drill pipe.
- 25 2. A method according to claim 1 wherein said drilling fluid is an oil base drilling fluid.
- 30 3. A method according to claim 1 wherein said drilling fluid is a water base drilling fluid.
- 35 4. A method according to claim 1 wherein said ratio is equal to or less than 4.
- 40 5. A method according to claim 1 wherein said drilling fluid is substantially the only drilling fluid employed.
- 45 6. A method according to claim 1 wherein said drilling fluid has a pH no greater than about 9.
- 50 7. A method according to claim 1 wherein said drilling fluid has dispersed therein no greater than about 14 weight percent based on the total weight of said drilling fluid of solid material having a specific gravity of no greater than 3.0.
